CLAIM

The ornamental design for a compressor with compressor shell, as shown and described.

DESCRIPTION

FIG. 1 is a top, front, right perspective view of a compressor in accordance with the present invention;

FIG. 2 is a top, rear, right perspective view thereof;

FIG. 3 is an elevated facing view thereof;

FIG. 4 is an elevated right side view thereof;

FIG. 5 is an elevated rear view thereof;

FIG. 6 is an elevated left side view thereof;

FIG. 7 is a top plan view thereof; and,

FIG. 8 is a bottom plan view thereof.

The broken lines depict portions of the article that form no part of the claimed design.

1 Claim, 8 Drawing Sheets(56)
